(57) **CLAIM**

The ornamental design for an eyelet cover, as shown and described.

DESCRIPTION

FIG. 1 is a top perspective view of an eyelet cover, showing my new design.

FIG. 2 is a front elevation view of FIG. 1, the rear elevation view being a mirror image thereof.

FIG. 3 is a left side elevation view of FIG. 1, the right side elevation view being a mirror image thereof.

FIG. 4 is a bottom perspective view of FIG. 1; and,

FIG. 5 is a bottom plan view of FIG. 1.

The broken lines showing the upper round portion in FIGS. 1-5 are included for the purpose of showing unclaimed subject matter only and form no part of the claimed design.

1 Claim, 2 Drawing Sheets
